SWITCH CONTROLLED ELECTRIC LIGHT SOCKET

Anthony Tiscione, Brooklyn, N. Y.

Application September 27, 1946, Serial No. 699,711

3 Claims. (Cl. 200—51.17)

1

The present invention concerns a switch controlled electric light socket and refers more particularly to a socket of novel form wherein the electric wires are held with a minimum of fastening means and contact is made between the wires through the electric lamp and a minimum of electric switch gear. This present socket is an improvement of my socket described in co-pending application Serial No. 638,804, filed January 3, 1946, now Patent No. 2,466,566, April 5, 1949.

One of the objects of the invention is to provide a switch wherein the movable switch member establishes electrical contact directly with an electrical conductor wire by a turning movement, and this movable member is constructed with a metallic conductor sheath and a slot which provides the interruption of the circuit connection when the member is turned, or moved.

Another object of the present invention is to provide an electric light socket which does not require screws for the attachment of the wires thereto.

A further object is to provide a socket with a different and simpler switch member.

Still another object is that the socket may be quickly installed.

Another and further object is that the socket be simple to operate and rugged in use.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevation partly in section of the light socket constructed in accordance with the present invention.

Fig. 2 is another side elevation looking from the right-hand side of Fig. 1.

Fig. 3 is a horizontal sectional view taken on the line 3—3 of Fig. 2.

Fig. 4 is a vertical sectional view taken on the line 4—4 of Fig. 2.

Fig. 5 is a vertical sectional view taken on the line 5—5 of Fig. 1.

Fig. 6 is a perspective view of the switch member per se.

Fig. 7 is a perspective view of the light socket constructed in accordance with a modification of the invention.

2

Fig. 8 is an enlarged section on the line 8—8 of Fig. 7.

Fig. 9 is a section on the line 9—9 of Fig. 8.

Fig. 10 is a vertical sectional view of the light socket constructed in accordance with another form of the invention.

Fig. 11 is a perspective view of the switch member used in the form of the invention shown in Fig. 10.

The switch controlled light socket, according to the form of the invention shown in Figs. 1 to 6, includes a socket 20 which comprises a cylindrical body 21 onto which a disc-like floor piece 22 with an upwardly extending flange 23 is snap fitted by the flange. The body 21 is composed of insulating or dielectric material and is formed with internal threads 24 for the reception of the threaded base of a lamp. An electric lead wire 25 is led into the side wall of socket body 21 extending tangentially of the threaded bore and extending thereto through a tangentially extending hole 26 which interrupts the threads 24 on their major diameter. Lead wire 25 is thus adapted to contact an electric lamp screwed into the threads 24. A second lead wire 27 is led into socket body 21 and lies flat along the floor piece 22 crossing the axis of the body 21.

The switch member 28 comprises a substantially cylindrical body of insulating material 29 such as dielectric plastic or ceramic encased for for about two-thirds or three-quarters of its circumference in conducting material 30, such as copper or other metal. The switch member 28 has an exposed shaft portion 31, a knurled handle portion 32 and a portion 33 square in cross section adjacent the exposed shaft portion 31 and extends radially from the body 21 through the wall thereof.

The exposed shaft portion 31 turns in a bearing hole formed in the cylindrical body 21, and the cylindrical body 28 extends through a bearing 34 secured in the floor 22. The squared end portion 33 of this switch body 28 engages the opposed springs 35, secured in the floor 22. The metal or copper sheath 30 is formed with a longitudinal slot 30' which exposes a portion of the insulating core 29 of the rotary switch element 28.

The electrical conductor wire 25 is stripped of its insulation and extended through the body 21, so that its metallic surface will have electrically conductive engagement with the threaded shell of an electrical lamp socket threaded into the socket 24. The rotary switch 28 is disposed in parallel relation to the hole which receives the conductor wire, and this wire is stripped of

its insulation, and connected to the springs 35. When the switch 28 is turned so that the conductor sheath 30 has electrical contact with the central electrode of the lamp, a circuit will be closed through the lamp coupled to the socket 24. When the switch 28 is turned so that the slot 30' thereof will be disposed in opposition to the central electrode of the lamp, the circuit will be broken, because this conical central lamp electrode will not have electrical conductive contact with the metal or copper sheath 30.

In a modified form of the invention shown in Figs. 7, 8 and 9, the mechanism of the previous form of the invention is incorporated and added to as follows:

The extended end of the shaft portion 31 of switch 28 has mounted thereon a ratchet 40 in the shape of a four pointed star. Revolvably mounted on shaft 31 is a pawl housing 42 having a flange 43 extending outwardly around the ratchet 40. A pawl pivot 44 is mounted in the pawl housing 42 and extended parallel to the shaft portion 31 and on the pivot 40 there is mounted a pawl 45. A housing cover 46 is attached in any well known manner to the flange 43 and an arm 47 there is attached to cover 46. At the free end of arm 47 is attached a chain 48 or any other flexible member and also there is attached an extension coil spring 49 anchored to a lug 49^a on the body 21. Upon pulling chain 48 downward, the shaft portion 31 will be caused to be revolved counterclockwise of Fig. 7 operating switch 28 as described in connection with the previous embodiment of the invention. Upon release of the chain 48, the arm 47 will be retracted to the elevated position and the pawl 45 will engage the next succeeding tooth of the ratchet 40 clockwise of Fig. 8 and the cycle of operation may be repeated. It is notable that proper operation of the pawl 45 and the ratchet 40 is assured by the springs 35 in resilient contact with the square portion 33 of the switch 28.

A further modified form of the invention is shown in Figs. 10 and 11 in which a socket 50 has a lead wire 51 led into the outer diameter of threads 52 formed in the socket 50 and extending tangentially thereto. A further lead wire 53 is led into the socket 50 and extends along the floor portion 54 thereof. A switch member 55 comprises a generally cylindrical body 56 of insulating material surrounded by a shell of conductive material 57 extending along the bottom thereof and around part of the top thereof, leaving a portion 56^a of the body 56 exposed. A reduced neck portion 58 is journaled in the socket 50 extending therethrough and terminating in a knurled knob 59.

At the other end of the switch member 55, a reduced axle portion 60 extends therefrom and is journaled in a bearing 62. A button 63 of generally conical shape extends downward from the switch member 55 and is resiliently contacted by a spring 64, preferably of U-shape, one of the legs thereof being fastened to the floor portion 54 and the other extending against the body of switch 55.

The conductive shell 57 of the switch member 55 is in electrical contact with lead wire 53 at all times and also in contact with lamp 65 in the on position of the switch (illustrated in Fig. 10) which is reached by pulling the switch member 55 to the left of Fig. 10. In so doing, spring 64 is compressed by button 63 during the first half of such movement and during the second half thereof is unloading and adding to the speed of

movement of the switch member 55. When the switch member 55 is in its leftmost position, the conductive shell 57 is in electrical contact with lamp 65 as well as with lead wire 53, thus completing an electrical circuit through lamp 65 back to lead wire 51 with which the lamp 65 is in contact.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In an electric light socket having a hollow socket body into one end of which a lamp having an end contact is screwed and the other end of which is closed by a wall, switch means within the socket body for making and breaking electrical contact with the end contact of the lamp, comprising a cylindrical body of insulation material within the socket body and engaging the end contact of the lamp and with its axis extended at right angles to the longitudinal axis of the lamp, a shell of conductive material mounted on said cylindrical body and extended along the bottom thereof and around part of the top thereof leaving a portion of said cylindrical body exposed, an electric lead extended into the socket body and connected to said shell, and means supporting said body for longitudinal slidable but non-rotative movement between a position in which the portion of said shell which extends across the top of said cylindrical body makes electrical contact with the end contact of the lamp or a second position in which the exposed portion of said cylindrical body contacts the end contact of the lamp, said supporting means comprising a reduced neck portion formed on one end of said cylindrical body and slidably extended through the side of the socket body, a bearing mounted on the end wall of the socket body adjacent the other end of said cylindrical body, and a reduced axle portion formed on the other end of said cylindrical body and slidably engaged in said bearing.

2. In an electric light socket having a hollow socket body into one end of which a lamp having an end contact is screwed and the other end of which is closed by a wall, switch means within the socket body for making and breaking electrical contact with the end contact of the lamp, comprising a cylindrical body of insulation material within the socket body and engaging the end contact of the lamp and with its axis extended at right angles to the longitudinal axis of the lamp, a shell of conductive material mounted on said cylindrical body and extended along the bottom thereof and around part of the top thereof leaving a portion of said cylindrical body exposed, an electric lead extended into the socket body and connected to said shell, and means supporting said body for longitudinal slidable but non-rotative movement between a position in which the portion of said shell which extends across the top of said cylindrical body makes electrical contact with the end contact of the lamp or a second position in which the exposed portion of said cylindrical body contacts the end contact of the lamp, said supporting means comprising a reduced neck portion formed on one

end of said cylindrical body and slidably extended through the side of the socket body, a bearing mounted on the end wall of the socket body adjacent the other end of said cylindrical body, and a reduced axle portion formed on the other end of said cylindrical body and slidably engaged in said bearing, and a knob mounted on the outer end of said reduced neck portion by which said cylindrical body may be moved between its two extreme positions.

3. In an electric light socket having a hollow socket body into one end of which a lamp having an end contact is screwed and the other end of which is closed by a wall, switch means within the socket body for making and breaking electrical contact with the end contact of the lamp, comprising a cylindrical body of insulation material within the socket body and engaging the end contact of the lamp and with its axis extended at right angles to the longitudinal axis of the lamp, a shell of conductive material mounted on said cylindrical body and extended along the bottom thereof and around part of the top thereof leaving a portion of said cylindrical body exposed, an electric lead extended into the socket body and connected to said shell, and means supporting said body for longitudinal slideable but non-rotative movement between a position in which the portion of said shell which extends across the top of said cylindrical body makes electrical contact with the end contact of the lamp or a second position in which the exposed portion of said cylindrical body contacts the end

contact of the lamp, a conical button mounted on the bottom of said cylindrical body with its apex extended toward the end wall of the socket body and spring mounted on the end wall of the socket body and engaging said conical button on one side of its apex, whereby when movement of said cylindrical body from one position to the other is started such movement will be retarded by said spring until the apex of said conical button passes said spring after which movement of said cylindrical body will be accelerated by said spring.
